RATE RESPONSIVE GUN SIGHT COMPUTER

John H. Holstein, Chicago, Ill.

Application July 23, 1945, Serial No. 606,698

5 Claims. (Cl. 33—49)

(Granted under the act of March 3, 1883, as amended April 30, 1928; 370 O. G. 757)

1

The invention described herein may be manufactured and used by or for the Government for governmental purposes without the payment to me of any royalty thereon.

This invention relates to mechanisms for determining angular or linear rates and for combining such rates with one or more variables to obtain a desired result or product. More particularly, the invention relates to the directing of guns at angularly moving targets wherein it is customary to cause the gun to lead the target by an angle at the gun, relative to the line from the gun to the instantaneous position of the target equal to the angular rate of movement of the gun multiplied by the range or the time of flight of the projectile, the two being approximately the same. In other words, ignoring super-elevation, the lead angle is the angle subtended at the gun by the change in target positions, between the time the projectile leaves the gun and the instant of impact.

It is an object of the invention to provide a rate responsive device of general utility, but particularly valuable for use in connection with the directing of guns, as previously mentioned.

A further object is to provide a rate responsive device, as aforesaid, that is entirely mechanical in construction, and one that is rugged and capable of withstanding the shocks incident to gun fire, while, at the same time, being relatively simple to construct, operate and service.

Another object is to provide a rate responsive mechanism that will differentiate between opposite directions of rotation so that the lead angle may be reversed for respectively opposite directions of travel of a target.

A still further object is to provide a rate responsive mechanism, as in the preceding paragraphs, in combination with a range, or time of flight multiplier, whereby the deflection angle may be measured or transmitted directly to correspondingly alter the angular relation or lead, between the gun and its sight or other means for establishing the instantaneous line between gun position and target.

Another object is to provide in combination with a rate responsive mechanism operated by elevational movement of the gun, a device directly connected to, and operated by said mechanism, to introduce the proper correction for super-elevation.

Other objects and advantages of the invention will become apparent as the description advances.

In the drawings:

Fig. 1 shows my invention as applied directly to a gun;

2

Fig. 2 shows a rate-responsive unit, partly in section, and suitable for use either to measure the angular movement of the gun in train or in elevation, and in both directions of movement;

Fig. 3 shows an elevation rate responsive mechanism such as is shown in Fig. 2, directly coupled to a mechanism for introducing the necessary corrections for super-elevation;

Fig. 4 is an enlarged sectional detail on line 4—4, Fig. 2, showing the brake or clutch mechanism provided to make sure that each governor rotates only in response to a corresponding direction of rotation of its input shaft;

Fig. 5 is an enlarged sectional detail view taken on the line 5—5, Fig. 2, showing the clutch mechanism provided to prevent the corresponding governor from rotating at a speed greater than that of its driving shaft;

Fig. 6 is a side elevation, partly in section, of a mechanism for multiplying angular rate by range or time of flight of projectile.

Fig. 7 is a front elevation corresponding to Fig. 6 and showing how the train and elevation multipliers may be mounted side by side for convenience of adjustment;

Fig. 8 is a front elevation of one form of sight and the connections for adjusting it vertically and laterally from the multiplier of Figs. 6 and 7;

Fig. 9 is a side elevation of the sight shown at Fig. 8 and

Fig. 10 is a side elevation of another form of sight suitable for use with the invention.

General description of invention

Referring to Fig. 1 wherein I have shown an embodiment of the invention applied to a gun, 10 indicates a fixed base of a gun placement, having a ring gear 11 fixed therewith. The base 12 of a gun mount is rotatable about a vertical train axis and carries a pair of trunnion supports 13. The cradle 14 of a gun 15 has trunnions 16 journaled in supports 13 and held in place by bearing caps 17. A bracket 18 is bolted to base 12 adjacent the periphery thereof and journals a shaft 19 having a pinion 20 keyed thereto and in mesh with ring gear 11. Shaft 19 is connected to a flexible shaft drive 21 connected to a rate device 22, so that, as the gun is trained by mechanism not shown, to rotate base 12 relatively to gear 11, the flexible shaft element 21 is rotated at a rate proportional to the rate of train.

A gear 23 is fixed to the end of trunnion 16, while a bracket 25 is fixed to bearing cap 17 and journals a second gear 24 to mesh with gear 23 so that gear 24 rotates as the gun is elevated

about the axis of trunnions 16. A flexible shaft 26 is connected to be driven by gear 24 and, in turn, drives a gear 27 journaled within a control box 28 carried by a bracket 29 bolted to support 13. Gear 27 meshes with and drives a pinion 30 within box 28 that in turn, is connected to drive a flexible shaft 31 extending to an elevation rate device 32. These rate devices 22 and 32 form an important part of the invention and will be subsequently described in detail. Suffice it to say, for the general description, that a flexible drive 33 leads from device 22 and is turned in proportion to the instantaneous value of the rate of train of the gun and enters a multiplier 34 where said rate is multiplied by range or time of flight. The resulting product appears as a rotation of a flexible shaft 35.

A sight 36 of any suitable type, is mounted on horizontal trunnions 37 carried by a support 38 that, in turn is pivoted upon a vertical axis on box 28. Support 38 has a gear sector 39 fixed therewith, concentric of its pivot axis, and adapted to be driven by a worm 40 connected with flexible shaft 35. As this shaft is driven in proportion to the proper lateral deflection or lead measured in the slant plane through the target, it will be clear that the gun is correspondingly deflected relatively to the target as it is moved to maintain the line of sight fixed upon the target.

Gear 27, previously mentioned, is mounted upon a shaft having thereon a bevel gear forming one side of a differential 41. A flexible drive 42 leads from elevation rate device 32, to multiplier 34, where the said rate is multiplied by time of flight and the resulting product is transmitted by flexible drive 43 to the other side of differential 41. The center of differential 41 is thus turned in accordance with the algebraic sum of gun elevation and elevation lead. Said center is connected by a flexible drive 44 with a worm 45 journaled on a vertical axis on one support 38 and meshing with a gear sector 46 fixed to sight 36. In this way the gun is given the proper lead in elevation relatively to the line of sight as it is elevated to maintain the line of sight upon the target. The construction of the multipliers will be explained in detail at a subsequent portion of the specification. The parts within box 28, may be protected by a door 47 having an opening 48 through which the adjustable parts of the multiplier may be operated.

The train rate mechanism

The train rate mechanism is shown in detail at Figs. 2, 4, and 5. A frame 50 is shaped to define an opening 51 in its lower portion within which fits a bearing sleeve 52. A shaft 53 is journaled within sleeve 52, by anti-friction bearings 54 and 55 and has a bevel pinion 56 fixed to its end. Shaft 53 is connected to be driven by flexible shaft 21, Fig. 1, in accordance with the rate of train of the gun. Frame 50 supports bearings 57 and 58 defining an axis at right angles to shaft 53. These bearings carrying a sleeve 59 having reduced ends as shown at Fig. 2. A second sleeve 60 is keyed to each reduced end and the right hand sleeve, as viewed in Fig. 2, has a bevel pinion 61 fixed thereto and in mesh with pinion 56. An outer governor sleeve 62 is mounted upon each sleeve 60, by anti-friction bearings 63. This sleeve is formed to support fly-ball or governor arms 64 and 65 for pivotal movement about axes normal to, and spaced from, the axis of sleeves 59 and 60. An inner governor sleeve 66 slidably fits sleeve 62 and is

shaped to pivotally support links 67 and 68, at its outer end. These links have their other ends connected to respective arms 64 and 65 so that, as sleeves 62, 66, arms 64, 65 and links 67, 68 rotate in unison, centrifugal forces act to move the weighted ends of arms 64 and 65 outwardly and thereby to move sleeve 66 axially within and along sleeve 62.

A shaft 69 is slidable axially within sleeve 59 and adjacent each end carries collars 70 and 71 whereby each sleeve 66 is swivelled upon said shaft. Thus, an increase in the rate of rotation of the right hand governor, Fig. 2, will cause a translation of shaft 69 to the left, while an increase in the rate of rotation of the left hand governor will cause translation of said shaft to the right.

Two governors are provided in order to distinguish between opposite directions of rotation of shaft 53; and I therefore provide over-running clutch devices between each outer sleeve 62 and sleeve 60. One of these is shown at Fig. 4, where it will be noted that sleeve member 69 carries the inner or toothed wheel 72, of a clutch device. The end portion of sleeve 62 closely surrounds member 72 and balls 73 are interposed in each of the pockets to thus form an over-running clutch. It will be understood that, while the clutch of the left-hand governor, Fig. 2, may be identical in construction, its toothed wheel is reversed with respect to wheel 72, so that one governor is rotated for one direction of rotation of shaft 53, while the other governor is rotated for the other direction of rotation of said shaft.

In order to make sure that friction or drag between the parts does not cause one governor to rotate when the rotation of shaft 53 corresponds to the rotation of the other governor, I provide a second over-running clutch comprising the toothed periphery of a disc 74, an outstanding rim 75 carried by frame 50 and balls 76 within the pockets thus formed. In this manner, each governor, while free to rotate in its intended direction is positively prevented from rotating in the opposite direction so that any errors that might be introduced by undesired rotation of either governor are prevented.

To assure instantaneous response to a decrease in the train rate, means are provided to prevent the governors from rotating faster than the rotation of sleeve 59, such as might take place, for example, when there is a sudden decrease in the rate of train. For this purpose, the inner surface of sleeve 66 is formed with cylindrical surfaces of two different radii, separated by a shoulder. The surface of larger radius is so dimensioned as to remain entirely out of contact with the balls 73 of a clutch shown at Fig. 5 when sleeve 66 is so positioned that said surface is directly opposite said balls. The surface of smaller radius is so dimensioned that when it overlies the balls 73, the clutch is rendered operative. The shoulder between the two surfaces will lie just outwardly of the plane of balls 73 when the governor is at rest while as soon as the governor starts to rotate, sleeve 66 is moved axially inward so that the smaller diameter portion is brought opposite to the plane of the clutch to thus effectively prevent sleeve 66 and its attached governor parts from rotating at a greater rate than sleeve 60. It will be obvious that the right hand governor as viewed in Fig. 2, is driven for a clockwise rotation of sleeve 59 as viewed in Fig. 4. From inspection of Fig. 5, it will be apparent that with such a direction of rotation, the speed-reducing clutch

does not operate so long as sleeves 62 and 66 are being driven by and from sleeve 60 through the clutch including balls 73. However, on a sudden decrease in speed of sleeves 59 and 60, the momentum of the governor parts will tend to cause them to continue rotation, or "coast" at the previous speed, whereupon, balls 78 ride up the teeth upon wheel 77 and effectively act to quickly equalize the speed of rotation of the governor parts with that of sleeves 59 and 60.

The governor at the left, Fig. 2, is a duplicate of the one just described except only that the respective toothed clutch wheels are reversed with respect to the corresponding wheels 72, 74 and 77 just described. The same reference numerals, primed, have therefore been used to indicate corresponding governor parts. Frame 50 is formed with rabbits 79 and 80 to receive the edges of protective covers 81 and 82. In this manner, shaft 69 is axially translated in one direction by one governor, and in the opposite direction by the other governor. In each situation, the amount of translation is proportional to the speed of rotation of shaft 53 and when one governor is controlling shaft 69, the other is positively prevented from interfering with, or in any way influencing, said control.

The elevation rate mechanism

In the case of train rate device 22, the translation of shaft 69 is directly transmitted to the multiplier for introducing the effects of range. However, in the case of the elevation rate device, an algebraic correction for super-elevation is required. This is conveniently introduced by the mechanism shown at Fig. 3 wherein the rate device itself may be a duplicate of the one shown at Fig. 2 and includes a shaft 85 that is connected to be driven by flexible shaft drive 31, Fig. 1. A bevel pinion 86 is fixed to shaft 85 and meshes with another pinion 87, fixed upon shaft 88 journaled in bearings 89 and 90 carried by the casing 91. A worm 92 is fixed to shaft 88 and drives a gear 93 pivotally mounted upon a shaft 94. An eccentric 95 is fixed to gear 93 and engages a bearing in one end of a link 96 having its other end pivotally connected at 96' with a link 97. The central portion of link 97 has pivotal connection as at 101 with a rod 69' guided for reciprocation in an aperture 99 formed in guide block 100. This block is attached to casing 91. It will be understood that rod 69' is translated in an amount and direction in proportion to the rate and direction of elevation (or depression) of the gun in the same manner as rod 69, Fig. 2, is translated for rate and direction of train.

At its other end, remote from link 96, link 97 is slotted, as at 102, to engage a pin 103 carried by the end of slidable rod 104 that, in turn, is connected with the core of flexible drive cable 42. It has previously been explained that this cable leads to the multiplier 34, subsequently described.

The throw or offset of eccentric 95 depends upon the constants of the instrument and is selected and so related to the gun that, when the gun is horizontal, the connected end of link 97 will be displaced to its maximum extent. As the gun is elevated, gear 93 is rotated by a like angle and the displacement of link 97 is reduced in accordance with the cosine of the angle of gun elevation in the manner necessary for super-elevation. Thus, when the gun is elevated 90°, the super-elevation correction is reduced to zero. The connections just described and including link 97 will be recognized as simulating, a simple

nomographic chart. Assuming that the perpendicular distance between the axes of rods 69' and 104 is equal to the distance from the axis of rod 69' to pivot 96', it is necessary only to make the scalar value of each unit of super-elevation, say 1°, twice the corresponding scalar value of a unit of lead due to angular rate, and to so connect the parts, that, for example, deflection of rod 69' to the left from zero or mid position corresponds to positive lead, while increasing values of super-elevation cause deflection of pivot 96' to the right. The linear deflection of rod 104 is then the algebraic sum of the deflections introduced by the rate and super-elevation adjustments, namely, total vertical lead.

To resume, the train rate device 22 consists solely of the parts shown at Fig. 2, and its shaft 69 is connected directly to flexible drive 33 while its shaft 53 is driven by direct connection with flexible shaft 21, Fig. 1. On the other hand, the elevation rate device 32, is driven by direct connection of its shaft 85 (corresponding to shaft 53, Fig. 2), with flexible shaft 31, Fig. 1, and consists of a rate mechanism exactly as shown in Fig. 2, plus the parts 86 to 104, Fig. 3. Thus the total translation of rod 104 is a true measure of total lead in elevation.

The range multiplier

The mechanisms for multiplying the individual train and elevation rates by time of flight or range are shown at Figs. 6 and 7; and it will be noted from Fig. 7, that the two are mounted side by side so that, if desired, their adjusting levers may be operated as a unit. A frame 107 has a base providing aligned bores 108 and 109 within which a rod 110 is slidably mounted. Bore 108 is of a diameter sufficient to accommodate an abutment washer 111, constrained to movement with rod 110 by collars 112 and 113, pinned to the rod. Compression springs 114 and 115 surround rod 110 and abut at one end against opposite sides of washer 111 and at their other ends against abutments provided by the frame and a nut 116 that serves to connect flexible drive 42 to shaft 110.

Shaft 110 may be conveniently formed in two sections, threaded into a coupling 117 of generally rectangular form and having a central slot 118 into which one end of a lever 119 projects where it is pivotally connected to coupling 117 by a pin 120. As shown at Fig. 7, the lever 119 is forked to form parallel arms, each of which is slotted, as at 121 and 122 to form parallel guideways within which slides a crosshead 123. This crosshead is pivotally connected with a rod or rack 124 that is slidably guided within aligned bores 125 and 126, in frame 107. Rack 124 drives a pinion 127 that is directly connected to flexible shaft 43 driving one side of differential 41.

An adjustable fulcrum is provided for lever 119, in the form of a crosshead 128 slidably guided by slots 121 and 122 and pivotally connected with a range slide 129 by means of a pin 130. Slide 129 is mounted for reciprocation in a direction normal to the direction of translation of rack 124 and rod 110, by means of a guideway 131 formed in frame 107. Slide 129 has a pin 137 at its top. An adjusting lever 133 is pivoted at 134 to an upstanding portion 135 of frame 107 and has therein a radial slot 132. Range slide 129 projects through a slot 136 in lever 133 and is connected thereto by pin 137 riding in slot 132. A sector 139 is attached to frame 107,

concentric of pivot 134. The periphery of this sector is provided with a range scale 140.

In operation, lever 133 is pivoted until its pointer 138 indicates the range of the target. This adjustment operates to move the fulcrum pin 130 for lever 119, to the proper position for that range and to thus vary the amount by which a given translation of rod 110, will translate rod 124 and rotate shaft 143, as will be obvious from inspection of Fig. 6. Thus, the rotation of shaft 43 will be proportional to the algebraic sum of the super-elevation and elevation rate lead angles, multiplied by range, in short, proportional to the amount by which the line of sight should be elevated or depressed relatively to the gun bore.

It will be noted from Fig. 7 that the range multiplier for lead in train, is mounted side-by-side with the elevation lead multiplier and that the construction thereof is a duplicate of the construction described in the immediately preceding paragraphs. The parts of this multiplier have been given the same reference numerals, primed, as are used in connection with the elevation rate multiplier. In view of the duplicate constructions it is thought that the previous description will suffice. It will be understood that pin 120' is translated by drive shaft 33, Fig. 1, and that its rack 124' rotates a pinion, corresponding to pinion 127, that, in turn rotates flexible drive shaft 35. Levers 133 and 133' may be moved individually to make any necessary spot corrections during firing.

Operation

As base 12 is rotated to train the gun, pinion 20 is rotated at a rate proportional thereto. This rate is conveyed to device 22, and there measured as a proportional translation of shaft 69 which is conveyed to multiplier 34. The output of the multiplier appears as a rotation of flexible shaft 35 and is applied to sight 36 by worm 40 to impart the proper angular relation between the line of sight and the gun bore in the slant plane of the bore. Similarly, as the gun is elevated or depressed, to maintain the line of sight upon the moving target, rotation corresponding to the elevation rate, is imparted to gear 24 and is conveyed by way of flexible shaft 26, gear 21, pinion 30 and flexible shaft 31, to shaft 85 of elevation rate device 32. This rate appears as a proportional translation of rod 69'. By proper initial calibration and adjustment shaft 85 effects rotation of gear 93 and eccentric 95 in synchronism with the elevation of the gun, so that a radius connecting the axes of gear 93 and eccentric 95 moves from the full correction position corresponding to zero quadrant elevation of the gun, through an angle of 90°, to zero correction position, as the gun elevates to a vertical position. These adjustments are algebraically added, as has been previously described, and the result conveyed over flexible drive 42 to multiplier 34, where the range factor is introduced and the product appears as a rotation of flexible shaft 43 and is thereby conveyed to one side of differential 41. As the other side of said differential is rotated proportional to actual gun elevation above datum, the center of the differential is rotated proportional to gun elevation plus or minus correct elevation lead. This combined value is then conveyed to rotate the sight relatively to the gun by the correct amount, by way of flexible shaft 44 and worm 45, as previously described. Thus the only adjustment necessary is for range, and this value may be introduced by simultaneously ad-

justing both levers 133 and 133'. The action is smooth and continuous so that the gun bore is at all times maintained at the correct angle relatively to the line of sight, to hit the target.

Sight modification

One suitable type of sight has been shown and described in connection with Fig. 1. Another type is shown at Figs. 8 and 9 wherein the sight may be adjusted by linkage directly connected to flexible drives. In these figures a base 140 may be mounted directly upon the gun cradle 14, or may be carried by casing 28, as in Fig. 1. A sight support 141 is pivoted upon base 140 on a vertical axis y, as by means of a circular projection 142 secured to, or integral with, support 141. Said support carries upstanding arms 143 and 144, each being apertured, as at 145 to provide bearings for trunnions 146 and 147 secured to the casing 148 of a sighting device of any suitable type. Support 141 has a forked portion 149 radially offset from axis y—y and to which one end of a link 150 is pivoted. The other end of link 150 is pivotally connected with an eye bolt 151 adjustably connected, as by turnbuckle 152, to the adjacent end of a flexible drive or Bowden cable 153. This cable corresponds in function to flexible shaft 35, Fig. 1, except only that its core, or driving element, moves axially relatively to the sheathing, instead of rotating relatively thereto. To use this type of cable, pinion 127, Fig. 6, may be omitted and the adjacent end of the cable directly connected to the projecting end of slide 124. Thus the sight is pivoted about the Y-axis, by an amount proportional to the output of the train section of multiplier 34.

The arms 143 and 144, have extensions above the telescope 148, that are bent together and apertured at their ends to provide a pivot 154 for a lever 155 that is connected at one end to telescope 148, by means of a link 156, pivoted at one end between a forked end of lever 155 and spaced apertured lugs 157 on the sight casing. The base 140 carries fixed uprights 158 and 159, connected at the top by a brace 160 having a boss 161 provided with a transverse bore 162. A short rod section 163 is slidably guided within bore 162 and has a transverse pin 164 at its lower end slidably within aligned slots in the forked end of lever 155.

50 A bell crank 165 is pivoted as at 166 to upright 159 and has the forked end of one arm, slotted to slidably engage a pin 167 fixed to a sleeve 172, swiveled between collars 173 and 174 on rod 163 at a point between pivot 154 and boss 161. The other end of bell crank 165 is also forked and provided with aligned slots slidably receiving a pin fixed in an eye-bolt 168, adjustably connected by a turnbuckle 169, with the adjacent end of a flexible drive or Bowden cable 170. As shown at Fig. 8, upright 159 is provided with a bracket 171 having an upright portion 172 to which the sheathing of cable 170 is attached.

Upon translation of the core of cable 170 by the drive, from the elevation section of multiplier 34, bell crank 165 is pivoted to thereby reciprocate rod 163, pivot lever 155 and move sight 148 about its trunnions 146, 147, by the correct angle of lead in elevation. As in the case of cable 153, the drive from the elevation rate section of multiplier 34, may be effected merely by connecting the adjacent end of its core directly to the end of rod 124', Fig. 7. The pinion corresponding to 127 of the train multiplier can then be omitted.

Fig. 10 shows a further modification of sight-75 ing device 175 having a side ocular 176 and trun-

ions 171 journaled in bearings formed on standards 178 secured to a base 179. This base may be rotatably mounted by brackets 180 and 181 upon a foundation 182 such as box 28, or upon the gun cradle, or any other part of the gun mount, as may be found desirable or expedient. The flexible drive 183 has its sheathing secured to a bracket 184 on foundation 182 while its core wire 185 is in contact with an arc of base 179 and is secured thereto as at 186. The casing 175 has a sector 187 attached thereto with its arcuate periphery concentric of trunnion 177. One end of the core 188 of flexible drive 189 is secured to sector 187 at 190. The outer or sheathing of drive 189, is fixed to a bracket 191, carried by standard 178.

It will be noted that drives 183 and 189 correspond to and are operated similarly to, drives 153 and 170 of Figs. 8 and 9, so that the correct angular adjustment is at all times applied to the sight. In those cases where the sight is mounted directly upon the gun cradle, differential 41, Fig. 1, may be dispensed with, and drive 43 may then be connected directly to the sight.

For the purpose of complying with the requirements of the patent statutes, the invention has been described in connection with a particular and special use, namely, the directing of a gun in firing upon a moving target. However, it will be appreciated that it is not so limited but that the elements of the invention are useful individually and in combination where it is desired to indicate or determine rates of rotation or translation or to combine such rates with other variables, either where said rotation takes place continuously in one direction or where it takes place in either direction. Hence I do not wish to be limited to the precise details of construction shown, nor to the particular combination disclosed. Numerous modifications and substitutions of equivalents will occur or be obvious to those skilled in this art. I therefore wish to reserve all such changes, modifications, and substitutions of equivalents as fall within the scope of the subjoined claims.

Having now fully disclosed my invention, what I claim as new and desire to secure by U. S. Letters Patent is:

1. In a rate mechanism for gun-fire control, a shaft operated by and in proportion to the elevation rate and elevation position of a gun, a rod, governor means driven by said shaft and connected to positively shift said rod in each of two opposite directions for a corresponding direction of rotation of said shaft, superelevation cam means connected to be directly adjusted by said shaft in accordance with the cosine of the angle of gun elevation, a linkage algebraically adding the shifting of said rod and the adjustment of said cam means, and output means operated by said linkage.

2. In a rate responsive mechanism for a gun movable in elevation, a pair of governors, means operating one governor by elevation of said gun and at a rate proportional to the rate of elevation, means operating the other governor by depression of said gun and at a rate proportional to the rate of depression, a rod connected to be moved in respective opposite directions by said governors, a superelevation cam connected to be moved proportional to the elevation angle of said gun, and output means operated jointly by said rod and cam in accordance with the algebraic sum of the movements thereof.

3. In a rate responsive mechanism for a gun movable in elevation, a pair of governors, means operating the governors by and in response to the rate of elevation and depression, respectively, of said gun, a rod connected to be shifted in one direction by one governor in proportion to the rate of actuation thereof and in the opposite direction by the other governor in proportion to the rate of actuation thereof, a link pivoted adjacent its central portion on said rod, means shifting one end of said link by and in accordance with the angle of gun elevation, and means driven by the other end of said link in accordance with the sum of the movements of said rod and shifting means.

4. In combination with a gun movable in elevation about a normally horizontal axis, a shaft rotated by and at a rate proportional to the rate of elevation of said gun, a first governor driven by one direction of rotation of said shaft, a second governor driven by rotation in the other direction of said shaft, said directions corresponding to elevation and depression of said gun, respectively, first means connected to be shifted in one direction by said first governor only and in the other direction by the second governor only, a superelevation cam shifted by and in accordance with the angle of gun elevation, second means operated in response to the sum of the shifting of said first means and cam, and third means adjustable in accordance with the range of a target and having an input driven by said second means and an output driven in proportion to said input multiplied by range.

5. In a gun sight, a base, a support mounted on said base for pivotal movement about a first axis, a line of sight device pivoted in said support for movement about a second axis normal to said first axis and determining a line of sight normal to said second axis, said line of sight and said axes being concurrent, a rod slidably axially on said base along said first axis, a lever pivoted on said support on an axis parallel to said second axis, and connected at one end to said rod and at the other end to said device, means pivoting said support in accordance with one lead angle of said gun, and means sliding said rod in accordance with a second lead angle of said gun.

JOHN H. HOLSTEIN.
